CHECKBOOK BINDER

Alexander Kensey, San Marino, Calif., assignor
to Coast Envelope Company, Los Angeles, Calif.,
a corporation of California

Application July 9, 1951, Serial No. 235,821

1 Claim. (Cl. 281—19)

1

My invention has to do with improvements in binders and relates more particularly to binders adapted to removably hold check filler pads. That is, in use, a bank gives to a customer a binder of this character in which check pads may be inserted as old pads become exhausted.

It is an object of my invention to provide a binder of this character which may be economically cut and formed from a single blank of material in a single cutting operation.

Another object is to provide a binder which embodies novel and simplified construction providing, at the same end portion, not only a retainer for the tab portion of a pad of checks to be inserted as a filler, but also provides a pocket to receive a passbook or the like, the pocket being closed at one end.

Other objects and advantages will appear hereinafter.

Heretofore such binders have been of more complicated construction. For instance, heretofore, in forming such binders, it has been deemed necessary either to provide the check pad tab retaining element and the pocket element at opposite ends of the binder, and to leave the pocket element open at both ends. Also, it has been deemed necessary to use a separate or second sheet in forming the pocket element. My invention overcomes those disadvantages.

Without intending thereby to limit the broader scope of my invention as defined by the accompanying claim, I shall now describe it in one of its presently preferred embodiments, for which purpose I shall refer to the accompanying drawings, wherein:

Fig. 1 is a top plan view of a blank from which my binder is formed;

Fig. 2 is a top plan view showing the binder in open position;

Fig. 3 is a top plan view showing the binder in folded position; and

Figs. 4 and 5 are enlarged sections taken respectively on lines 4—4 and 5—5 of Figs. 3 and 2.

Referring now to the drawings, I first cut from a sheet of flexible material, such as paper, leather or imitation leather, a blank 5 having scored or weakened transverse folded lines 7, 8 and 9 defining a left end portion 15, a contiguous portion 16, next contiguous portion 17 and a flap portion 19. In the completed binder, parts 15 and 16 form the bottom portion of the binder, while part 17 forms the top. I then mount in the blank a pair of interengaging snap fastener elements 22a, 22b of conventional construction.

Part 15 is provided with relatively short mar-

2

ginal side extensions 25, and has its outer end edge curved or recessed at 27 to define a pocket entrance edge as shown in Fig. 2. Adjacent the fold line 7, I provide a transverse cut or slit 30, the purpose of which will be explained.

The undersurface of each of the extensions 25 is coated with a suitable adhesive 32 and are folded over on the contiguous portions of part 15, after which the part 15 is folded over on the part 16 along the line 7, thereby adhering the extensions to the part 16 to form a pocket 35 for the reception of a passbook or the like (not shown) to be inserted or removed through the pocket opening 27. This folding operation leaves the slit 30 adjacent the left-hand end edge of the completed device as shown in Fig. 2, so that the tab portion 40 of a checkbook filler C may be inserted and retained in the manner shown in Fig. 5, while the pad of checks rests against the parts 15 and 17.

To further fold the binder into a position to be carried in one's pocket, it is then folded along the lines 8 and 9 which brings the flap portion 19 into position beneath the bottom portion 16, in which position the fastener elements 22a, 22b may be interengaged to hold the binder in such folded position.

I claim:

1. A check pad filler binder comprising an elongated sheet of flexible material having three longitudinally spaced transverse fold lines intermediate its ends defining end portions, a bottom portion and a front portion, the first of said end portions being folded over onto the upper face of said bottom portion and having lateral side extensions folded inwardly and adhered to the upper face of said bottom portion to form a pocket, and a fastener carried by said bottom portion, the second of said end portions being foldable along one of said fold lines and carrying a fastener cooperable with said first named fastener; the first of said end portions having a transverse slit therein adjacent its intersection with said bottom portion.

ALEXANDER KENSEY.
